UNITED STATES PATENT OFFICE.

JAMES EDWARD MINSON, OF RICHMOND, VIRGINIA, ASSIGNOR TO RICHMOND CEDAR WORKS, OF RICHMOND, VIRGINIA, A CORPORATION OF VIRGINIA.

ICE-CREAM FREEZER.

Application filed April 10, 1923. Serial No. 631,151.

The object of this invention is to simplify and improve the gearing and the manner of mounting the same upon the top of the tub, to the end that the structure will not only be durable, but will be inexpensive to manufacture, as more fully hereinafter set forth.

In the drawing—

Fig. 1 is a perspective view of the top portion of an ice-cream freezer showing my invention applied thereto;

Fig. 2 is a similar view with the gearing removed;

Figs. 3, 4 and 5 are views of details hereinafter described.

Referring to the annexed drawing by reference characters, 10 designates the gearing-carrying bar which, as usual, is adapted to extend across the top of the tub and be removably attached thereto. This bar 15 consists of a single sheet of steel having its longitudinal edges bent downwardly to form flanges 11 extending the full length of the bar. When this bar is in place on the tub, the flat under face of the main part of 20 the bar rests solid against the upper edge of the tub and the depending flanges 11 fit down into notches 12 formed in the upper edge of the tub, thus giving the gearing-carrying member a strong solid support on 25 the tub and at the same time permitting this member to be constructed of light sheet steel.

At one end of the bridge-member, there 30 is affixed to the outer side of the tub a metal plate 13 whose upper edge extends above the rim of the tub and is provided with a slot 14 through which extends a tongue 15 formed integral on the top plate of the bridge member, this tongue being curved 35 upwardly so as to interlock with the ear 13 when the tongue is passed through the slot 14 when the bridge-member is swung down on the top of the tub. At the opposite side 40 of the tub, a similar plate or ear 13 is attached to the tub, and adapted to engage in the slot 14 of this latter ear is the locking 45 end of a lock-lever 16 pivotally mounted on the top face of the bridge-member. The top plate of the bridge-member is provided 50 with a transverse slot 17 up through which the reduced upper end of the ear 13 extends, so as to bring the slot 14 slightly above the upper face of the bridge-member, so that 55 said slot will lie in position to receive the outer end of the locking-lever. By thus

making the two upstanding ears exactly alike, it will be observed that the bridge-member is thereby made reversible, end-for-end, so that in replacing the gearing on the tub it will not be necessary to bother 60 about selecting the proper ear for engagement with the locking-tongue 15; this facilitates considerably the replacing of the gearing on the tub.

The freezer-can and dasher arrangement 65 are constructed as usual. The can top 18 is provided with a cog-gear 19 and an upstanding journal 20 which engages a hole in the top plate of the bridge, and the dasher 21 is provided with a squared shank 22 70 which extends up through a hole in the top of the cover and engages in a square hole formed in a bracket 23. The gear 19 is driven from a driving-gear 24 affixed to the squared part of a short shaft 25 which has 75 it upper end journaled in a hole in the bridge-member and is provided with a hand-crank 26. The lower end of the shaft is journaled in a hole formed in a plate 27 which is riveted to the under side of the 80 bridge-plate at 28. It will thus be seen that the rotation of the crank-handle in a horizontal direction will drive the cream-can in one direction, while the dasher is held stationary by the squared shank 22 and the 85 bracket 23.

A feature of importance lies in the manner of supporting the shaft 25. The lower end of the shaft extends, as stated, through a hole in the supporting-plate 27, and the 90 shaft is prevented from dropping down through this hole by the squared portion which engages the driving-wheel. The supporting-plate 27 is the full width of the channel formed by the depending flanges 11 95 and is bent transversely at 29 and 30 to form an upwardly-extending wall 31 and an outwardly-extending securing-flange 32 which lies against the under face of the sheet-metal bridge-plate. In this way, the 100 driving-gear is housed, a substantial support is provided for the driving-shaft 35 and the supporting-plate for this shaft is utilized to brace the sheet-metal bridge-member.

It will be observed that the locking-end 105 of the lever 16 is a broad flat plate approximately equal in width to the length of the slot 14, thus providing a broad substantial engagement with the upstanding ear on the 110

bucket, to thereby hold the bridge squarely down on the tub and prevent twisting and rocking of the thin sheet steel bridge.

What I claim is:—

- 5 In an ice-cream freezer embodying a wooden tub having two pairs of separated narrow notches formed in its rim at diametrically opposite sides, upstanding slotted ears affixed to the tub between said notches,
- 10 a bridge-member consisting of a piece of sheet metal having its longitudinal edges bent down to form flanges, said flanges fitting down in said notches and extending

through the full thickness of the tub-wall 15 to permit the body portion of the bridge-member to rest flat against the rim of the tub, gearing carried by said bridge-member, and fastening means carried by the bridge-member and adapted to engage said upstanding ears to hold the body of the 20 bridge-member solidly against the tub-rim and the flanges down in said notches.

In testimony whereof I hereunto affix my signature.

JAMES EDWARD MINSON.
